UNITED STATES PATENT OFFICE.

MARK FLATHER, OF NASHUA, NEW HAMPSHIRE.

EXTENSION-TABLE.

1,159,000.

Specification of Letters Patent.

Patented Nov. 2, 1915.

Application filed August 8, 1912. Serial No. 713,958.

To all whom it may concern:

Be it known that I, MARK FLATHER, a citizen of the United States, and a resident of Nashua, county of Hillsboro, State of New Hampshire, have invented an Improvement in Extension-Tables, of which the following description, in connection with the accompanying drawings, is a specification, like characters on the drawings representing like parts.

This invention relates to extension tables, and among other objects provides an improved removable top, and improved slides for extensibly connecting the top with the pedestal or support of the table.

The character of the invention may be best understood by reference to the following description of an illustrative embodiment thereof disclosed in the accompanying drawings, wherein:

Figure 1 is a plan of an illustrative table embodying the invention having its top removed to disclose the construction of the slides beneath the same; Fig. 2 is a vertical section through the slides taken on line 2—2 of Fig. 1; Fig. 3 is a section taken on line 3—3 of Fig. 2; Fig. 4 on an enlarged scale is a section taken on line 4—4 of Fig. 3; Fig. 5 is a vertical section through the table; Fig. 6 is a side elevation of portions of slides showing their assembled relation; and Fig. 7 is a similar view showing the relation of the slides in the course of the removal of the top from the pedestal.

Referring to the drawings, the illustrative table shown therein as embodying the invention comprises a pedestal or support (Fig. 5) split vertically to provide sections 1—1 of usual construction having feet 3 at their lower ends and bridge blocks 5 and 6 at their upper ends secured to said sections by bolts 7 (Fig. 1).

The top of the table comprises main sections 9 and 10 which are adapted to be extended or separated to permit the introduction of fillers (not shown) between them. To permit their extension the top section 9 is fastened to slides 11, 11, coöperating with similar slides 15, 15 secured to the pedestal bridge block 5; and the top section 10 is fastened to slides 17, 17 coöperating with similar slides 19, 19 secured to the pedestal bridge block 6.

For small extensions of the table the pedestal sections preferably remain closed, and the top sections when pulled apart cause

their slides to move relatively to the pedestal slides. To limit this movement the top slides 11 have stop pins 25 and the pedestal slides 15 have stop pins 27 arranged in alinement, so that when the slides 11 are drawn out a predetermined distance the stops 25 will engage the stops 27 and prevent further extension of said slides 11 relatively to the slides 15. Continued separation of the top sections 9 and 10 will drag the pedestal slides 15 along with the top slides 11 and the pedestal slides 19 along with the top slides 17. As a result, the pedestal sections will separate and their slides will move relatively to one another. To limit the relative movement of the pedestal sections they have stops 29 and 31 for engagement with one another.

An important feature of the invention relates to the connection of one slide with another, whereby the friction between them and the work in extending the table is reduced to a minimum. To this end each slide is provided with a guideway typified herein as a track 35 (Fig. 4) preferably U shaped to provide upper and lower rails 35^a, 35^b, said tracks being seated in a channel 36 (Fig. 2) in a face of the slide and secured thereto by screws or otherwise as desired. The opposite face of the next adjacent slide is provided with follower means typified herein as upper and lower rollers 37 adapted to travel along the rails of the track 35 when the latter is interposed between them. Said rollers are journaled on studs 39 projecting inward from brackets 41 secured to the slide by suitable screws. To assist in supporting the brackets on the slides the brackets may have portions bent therefrom to present lugs 43 set into kerfs in the slides. To keep the rollers on their tracks they may have flanges 45 protected by guards 41^a projecting from the brackets 41. The engagement of the roller flanges with the sides of the rails will prevent lateral movement of the slides away from one another. The outer faces of the brackets 41 may bear against the faces of the next adjacent slides and limit the approach of the slides toward one another. The corners of the brackets may be rounded as shown in Fig. 3 to enable them to readily slide along the slides opposite thereto.

It is highly desirable in extension tables to detachably connect the top of the table to its pedestal so that a variety of tops may

be used on the same type of pedestal, and so that the table may be conveniently packed for shipment and be readily moved from one room to another. The track and roller connections described lend themselves advantageously to this purpose and I will now describe a simple arrangement of them which enables the separation of the top from the pedestal.

10 As stated, some of the slides are secured to the top sections and other slides are secured to the pedestal sections. Therefore the top section slides will be removed with the top sections.

15 The tracks described do not extend the entire lengths of the slides, but merely along portions of their lengths and are located adjacent the ends of the slides (Fig. 1). Adjacent opposite ends of the slides are 20 sets of rollers each comprising upper and lower rollers as described. By this arrangement the slides 11 of the top section 9 are each connected to their respective slides 15 of the pedestal section 5 by a track and a 25 set of rollers on one cooperating with a set of rollers and a track on the other (Figs. 6 and 7). The upper and lower rollers of each set are not in vertical alinement, but the upper roller of the slide 15 is offset to the right from its lower roller (Figs. 3 and 30 6) and the upper roller of the set applied to slide 11 is offset to the right of its lower roller (Fig. 6) for a purpose to be described.

35 When it is desired to remove the top section 9 from the pedestal it is drawn out from the pedestal, together with its slides 11 until arrested by the engagement of the top slide stops 25 with the pedestal slide stops 40 27 (Fig. 6). When said top section has been pulled out this far the inner ends of the tracks of the top slides 11 will have passed beyond the upper rollers of the pedestal slides 15, but said tracks will still rest 45 on the lower rollers of said pedestal slides as shown at the left of Fig. 6. When in this predetermined position, the top slide tracks, being no longer limited by the upper rollers of the pedestal slides, permit the top 50 section and slides to be lifted or rocked in substantially vertical planes transversely to the lengths of the pedestal slides 15 about the upper rollers of the top slides 11 on the tracks of the pedestal slides 15 as fulcrum. 55 A slight upward rocking of the top section 9 and its slides will lift the top slide stops 25 up out of alinement with the pedestal slide stops 27. The top slides, being no longer limited by the engagement of said stops, are 60 then free to be drawn farther away from the pedestal sufficiently for the top slide rollers to clear the pedestal slide tracks. The top section 9 is secured to end portions of the top slides and therefore tends to rock the top 65 slides in a contra-clockwise direction (Fig. 6)

relatively to the pedestal slides. To prevent any possibility of such rocking when the top and pedestal stops 25 and 27 engage one another to limit the outward extension of the top section the top slide rollers are at a 70 short distance from the ends of their tracks. After the stops have been lifted out of alinement, however, the top slides may be freely drawn to move the top slide rollers beyond the ends of the pedestal slide tracks. This 75 marks the completion of the separation of the top section and pedestal slides and the top section 9 is then completely removed from the pedestal. The other top section 10 is provided with a similar arrangement of 80 stops, tracks and rollers to that described in connection with the top section 9 and therefore may be removed in a similar manner.

When it is desired to replace the top section 9 back on the pedestal it is merely necessary to present the top slide rollers to the pedestal slide tracks accompanied by a downward tilt of the top slides to enable the top slide stops 25 to come into alinement with the pedestal slide stops 27. This 85 movement will bring the top slide tracks to and upon the lower rollers of the pedestal slides and the top and pedestal slides will 90 then be assembled in position in readiness for any desired extension in use.

95 The top slide rollers have a sufficiently free contact with the pedestal slide tracks to permit the slight rocking of the top slides which is necessary to enable the top slide stops to pass the pedestal slide stops. To 100 prevent excess rocking of the top slides to avoid cramping the top slide rollers against the pedestal slide tracks and to facilitate the guidance of the top slide stops relative to the pedestal slide stops, guides 27^a may be 105 provided for the top slide stops 25. Each of said guides may conveniently be substantially U shaped and be set in a recess in the face of the pedestal slide and be secured by a screw or otherwise as desired. The guide 110 preferably is of a length corresponding to the distance of the top slide lower rollers from the ends of the pedestal slide tracks when the top and pedestal slide stops 25 and 27 are in engagement, to limit the rocking 115 of the top slides relatively to the pedestal slides until after said top slide lower rollers have passed beyond the ends of the pedestal slide tracks. To facilitate the entrance of the top slide stops 25 to the guides 27^a the 120 ends of the latter may flare somewhat as at 27^b. To facilitate the rocking of said top slides relatively to the pedestal slides the roller flange guards 41^a projecting from the brackets 41 may be rounded as at 41^b. To 125 enable the top slides 11 to clear the bridge block carrying the pedestal slides 15 the lower inward corners of the top slides 11 may be rounded as at 11^a.

130 It will be observed that the extension lim-

iting stops are fast on their slides and that there are no latches or locking devices to be operated to detach a top section from the pedestal, but it is merely necessary to pull the section out and give the same a slight lifting tilt to effect its removal from the pedestal.

There will be no danger of giving the top section an accidental removing tilt since in 10 use any weight on the table would tend to press the same downward, and to remove the section it is necessary to lift the same upward.

The track and roller connections for the 15 slides enable the table to be readily extended with ease. There are no wood tongues and grooves liable to swell, stick and render extension difficult. The tracks and rollers are simple and strong in construction, may 20 be readily applied to the slides and effectively hold the same in proper relation.

Having described one embodiment of the invention without limiting the same thereto, what I claim as new and desire to secure by 25 Letters Patent is:

1. An extension table comprising in combination, main top sections, a pedestal therefor, a set of relatively extensible slides connecting each of said sections to said pedestal, and means detachably connecting the 30 slides of each set comprising guideway means and coöperating follower-and-stop-means upon the slides of such set, said follower-and-stop-means and guideway means being 35 relatively located and arranged to permit parts of said follower-and-stop-means to be relatively moved out of engagement with each other to enable the removal of the follower means from said guideway means, 40 upon adjustment of a slide of such section in a vertical plane when substantially at its outward limit of extension away from said other section.

2. An extension table comprising, in combination, a pedestal; main top sections thereon; a set of relatively extensible slides connecting each of said top sections to said pedestal; and means detachably connecting slides of each set comprising coöperating 50 followers and guide way means, said guide way means having portions for receiving said followers, one of the latter being located and arranged for introduction to and removal from one of said portions and the other of said followers being located and arranged for introduction to and removal from the other portion on adjustment of a slide of a top section in a substantially vertical plane when in a predetermined position 55 of normal outward extension away from said pedestal and the other top section.

3. An extension table comprising, in combination, a pedestal; main top sections supported thereby; a set of relatively extensible slides connecting each of the top sections 60

to said pedestal; and means detachably connecting slides of a set comprising coöperating followers and guide way means, said guide way means having portions for receiving said followers, one of the latter being 70 located and arranged for introduction to and removal from one of said portions, and the other of said followers being located and arranged for introduction to and removal from the other portion on adjustment of one slide 75 in a substantially vertical plane transversely to the length of the other slide when the slides are in a predetermined relation, said slides having provision permitting uninterrupted relative adjustment thereof from any 80 of their positions of extension to said predetermined relation.

4. An extension table comprising, in combination, a pedestal; main top sections supported thereby; a set of relatively extensible slides connecting each of the top sections to said pedestal; and means detachably connecting slides of a set comprising coöperating followers and guide way means, 85 said guide way means having portions for 90 receiving said followers, one of the latter being located and arranged for introduction to and removal from one of said portions, and the other of said followers being located and arranged for introduction to and removal from the other portion on adjustment of one slide in a substantially vertical plane transversely to the length of the other slide when the slides are in predetermined relation, each of said top sections being 95 adjustable to bring its slides in said predetermined relation independently of adjustment of the other top section.

5. An extension table comprising, in combination, main top sections; a pedestal therefor; a set of relatively extensible slides connecting each of said sections to said pedestal; means to limit extension of said slides away from one another; and means detachably connecting slides of each set comprising coöperating followers and guide way means, 105 said guide way means having portions located and arranged for permitting removal of said followers therefrom on adjustment of a slide of one section in a vertical plane when substantially at its outward limit of extension away from said other section.

6. An extension table comprising, in combination, main top sections; a pedestal; a set of relatively extensible slides connecting each of said sections to said pedestal; and means detachably connecting slides of each set comprising coöperating followers and guide way means, the latter having portions 120 located and arranged for permitting removal of said followers therefrom on lifting of one of the slides of a section in a substantially vertical plane transversely to the length of the other slide when the slides are in pre- 125 130

determined relation of outward extension, said guide way means having provision for preventing dropping of said top sections from the level of the table top when the sections are extended outward away from one another with their slides in said predetermined relation.

In testimony whereof, I have signed my name to this specification in the presence of two subscribing witnesses.

MARK FLATHER.
